UNITED STATES PATENT OFFICE.

SIDNEY JOHN ROSS AND HARRY SCHOFIELD, OF LONDON, ENGLAND.

APPARATUS FOR THE DISTILLATION OF OILS.

1,204,492.

Specification of Letters Patent. Patented Nov. 14, 1916.

Application filed December 22, 1915. Serial No. 68,185.

To all whom it may concern:

Be it known that we, SIDNEY JOHN Ross and HARRY SCHOFIELD, both subjects of the King of Great Britain, and residing at 117 and 118 Leadenhall street, E. C., in the city of London, England, have invented certain new and useful Improvements in Apparatus for the Distillation of Oils, of which the following is a specification.

10 This invention has reference to the heating and distillation of oils, and more particularly relates to the treatment of petroleum or mineral oils for the production of various distillates, for example petroleum spirit, illuminating oils, gas oils, or lubricating oils.

Now according to this invention, saddles or casings of non-conducting or heat-insulating material are provided on the furnace 20 flue or flues of the still or boiler and are combined with hoods or nozzles preferably directed forward so that circulation may be set up in a longitudinal direction or along the top of the boiler flue. The hoods are 25 generally but not necessarily placed where the maximum heat is obtainable, thus effecting increased rapidity of circulation in the boiler or still, due to the great difference in temperature.

30 The hoods or nozzles may be provided with separate draw-off pipes for the more volatile distillates. They may as distinguished from steam boiler circulators, be arranged to project well above the liquid level 35 to cause spraying or foaming to facilitate the liberation of the products or distillates.

In order that the invention may be clearly understood and readily carried into effect reference will now be made to the examples 40 shown in the accompanying diagrammatic drawings in which:

Figure 1 is a longitudinal section of a boiler or still with a single furnace flue having such a circulator device applied thereto. 45 Fig. 2 is a section thereof on the line 2—2, looking toward the right, while Fig. 3 is a detail section on the line 3—3 of Fig. 1. Fig. 4 is a detail view to a larger scale hereinafter referred to.

50 Referring more particularly to Fig. 1:—*a* is the shell of the boiler or still which in this case is shown for the sake of simplicity as having only a single longitudinal flue *b* after the manner of a Cornish boiler, com-

municating with an uptake or chimney such as *b*¹ at the right-hand end thereof.

c c are the heat-insulating circulator saddles, diaphragms or shields, which are concentric or practically so with the furnace flue *b*. They may be formed (see Fig. 4) 60 of thin sheet material, such as iron sheets *c*² combined with heat-insulating material *c*³.

The saddles may be fitted on to the ordinary flanges (not shown) of the flue *b*. They may however have turned-down ends, 65 or be provided with flanged rings *c*¹ at the ends as indicated in the sectional view, Fig. 3. In other cases they may be left open at the ends.

d d are the directing hoods or nozzles, 70 which in the example shown are of inclined or wedge-shape and are forwardly directed. They are fitted over the middle of the saddle so that the convection currents, set up by the high temperature due to the wall of the 75 furnace flue, flow up into them as indicated in Fig. 2.

The saddles may be provided in any convenient way with an insulating sheathing or layer in order to confine the heat more effectually to the narrow circulation space as above referred to.

An example of such an arrangement is shown in detail section in Fig. 4, where *c*² 85 *c*² are two curved sheets of metal having between them a layer of cement, mica, asbestos or other suitable heat insulator *c*³, the whole being held together by bolts, rivets or otherwise.

The above improvements lead to economy 90 by reducing fuel consumption, diminishing the temperature of distillation and reducing or entirely dispensing with the use of steam as an aid to the liberation of products, besides causing less cracking of the oil and 95 yielding improved products. The stills, too, are less liable to be damaged by over heating or burning, and caking or settlement of residue in the still bottom is less likely to occur.

In some cases the circulating saddles or their hoods or cowls may be provided with uptake pipes or funnels, to conduct more or less of the distillates direct to the take-off pipes, or to the outlets from the boiler or 105 still. Such an arrangement is illustrated in connection with the left hand hood of Fig. 1, *e* being a pipe which is fitted over a suit-

able opening in the top of the hood and serves to conduct a portion of the distillates direct to an off-take pipe f . In this way the vapors or a portion of them can be removed directly, without having to enter the main vapor space in the top of the still, and thus without having to mix with the other portions of the distillates.

Such an arrangement may be applied conveniently in connection with fractional distillation so that the light distillates can be removed thereby in the early stages, after which the pipe f may be closed by a valve f' and the operation continued in the still itself in the ordinary way.

Obviously the invention may be modified in various ways in carrying the same into practice without departing from the general nature thereof.

20 We claim:—

1. In an oil-heating or distilling apparatus, the combination of a furnace flue, a heat insulating saddle mounted on same, and a nozzle on said saddle for directing the circulation, substantially as described.

2. In an oil-heating or distilling apparatus, the combination of a furnace flue, a heat insulating saddle mounted thereon, and a tapered or wedge-like hood at the top of said saddle extending lengthwise thereof parallel with the flue, substantially as described.

3. In an oil-heating or distilling apparatus, the combination of a furnace flue, heat insulating saddles mounted thereon, and nozzles on said saddles for directing the circulation in a longitudinal direction, substantially as described.

4. In an oil-heating or distilling apparatus, the combination of a furnace flue, a heat insulating saddle mounted thereon, a nozzle on said saddle for directing the circulation in a longitudinal direction, and a draw-off

pipe mounted on the top of said nozzle for removing the distillates directly from said nozzle, substantially as described.

5. In an oil-heating or distilling apparatus, the combination of a furnace flue, a saddle thereon formed of metal sheets with heat-insulating material between them, and a wedge-shaped nozzle extending along the top of said saddle and serving to discharge the liquid longitudinally, substantially as described.

6. In an oil-heating or distilling apparatus, the combination of a still of cylindrical shape, a furnace flue extending along said still, a saddle mounted on said flue and a nozzle at the top of said saddle, such saddle and nozzle being formed of heat-insulating material, substantially as described.

7. In an oil-heating or distilling apparatus, the combination of a cylindrical still or boiler, a furnace flue in same, a heat insulating saddle, and a nozzle to direct the liquid along the top of the flue and so set up longitudinal circulation in the boiler, substantially as described.

8. In an oil-heating or distilling apparatus, the combination of a still or boiler, an internal furnace-flue for heating the same, a non-conducting saddle mounted on top of said flue, a tapered nozzle extending all along said saddle and opening only at its wider end, and a pipe leading up from the hood through the vapor space in the still or boiler to the off-take pipe, substantially as described.

In testimony whereof we affix our signatures in presence of two witnesses.

SIDNEY JOHN ROSS.
HARRY SCHOFIELD.
